ARNOLD CRAWFORD MASSIE, OF NEW YORK, N. Y.

BOTTLE-CAPPING DEVICE.

1,386,131.

Specification of Letters Patent. Patented Aug. 2, 1921.

Application filed June 10, 1920. Serial No. 388,027.

To all whom it may concern:

Be it known that I, ARNOLD C. MASSIE, a citizen of the United States, residing at New York, in the county of New York and 5 State of New York, have invented certain new and useful Improvements in Bottle-Capping Devices; and I do hereby declare the following to be a full, clear, and exact description of the invention, such as will 10 enable others skilled in the art to which it appertains to make and use the same.

This invention relates to bottle capping devices; and it relates more particularly to manually operable bottle capping devices of 15 a type best suited to operation on a small scale, as for domestic purposes and the like.

The invention has to do especially with devices for applying crown cap closures to bottles, jars and the like. In order to apply such closures effectively, it is necessary 20 that the crown cap first be placed and held in position on the bottle or jar mouth, with the cork or other sealing disk preliminarily compressed a predetermined amount, the 25 skirt of the crown cap so held being then crimped over the bead provided for that purpose on the neck of the bottle or jar.

In prior machines the cap was seated on the bottle and the skirt crimped by 30 mechanism which would compress or yield, when the pressure on the bottle exceeded a predetermined amount, in order to prevent breakage of the container. This was necessary because of the fact that commercially 35 available bottles of a given capacity, such as pints or quarts, differ considerably in height owing to imperfections in manufacture, a variation of from three-eighths to one and one-half inches being 40 fairly common in both pint and quart bottles of the type commonly used to contain beverages, etc.

In the numerous capping machines heretofore devised the capping of the bottle 45 occurs first, and then follows the functioning of the means which are provided to allow for the variation in the height of the bottles. Furthermore, such machines have been mostly of complicated character and 50 adapted for more or less automatic operation on a large scale.

It is a principal object of the present invention to provide a simple and inexpensive bottle capping tool which can be readily 55 set up and used in the ordinary kitchen,

which is of solid and durable construction and which can be operated even by an unskilled person with the certainty that the bottle will be capped and sealed effectively, regardless of such variations in height as 60 ordinarily characterize bottles of the usual type. In this tool, the functioning of the mechanism for allowing for or compensating for the variation in height of the bottle takes place first, so that the top surface 65 of each and every bottle-neck or mouth is brought into a predetermined relation to the capping mechanism at the outset. That is to say, the bottle is first accurately gaged between the bottle support and the capping 70 head. Then, with a substantially fixed or predetermined stroke of the compression foot, the cork or other disk is compressed a definite distance sufficient to insure a minimum necessary sealing pressure regardless 75 of the hardness or softness of the cork disk, and thereafter the capping throat device, which crimps the skirt of the crown, is given a predetermined stroke which is substantially uniform for all bottles. Of course 80 the absolute magnitude of the pressure produced by thus seating the cap will depend on the hard or soft nature of the cork; but it is always great enough to give a perfect seal although never sufficient to break a 85 bottle. So also the pressure of crimping the skirt depends upon the tin, but is not sufficient to break the bottle.

Briefly described, bottle capping apparatus embodying the present invention 90 comprises three principal parts or members, namely, a table or base for supporting the bottle, a compression foot whereby, in co-operation with said table the requisite pressure on the cap is obtained, and a capping-throat or crimping device which serves to lock the bottle cap around the locking bead with which the bottle neck or mouth is provided. In the simple form of the invention, complexity is avoided and other 100 advantages are attained by making these three parts or members independently operable by manual means in a manner to be more fully hereinafter described, and, broadly speaking they coöperate thus: The 105 bottle support or table is provided with actuating means whereby its position may be adjusted quickly in the direction of the bottle length in such manner as to thrust the mouth of the bottle upward, so that 110

the cap with which it is preliminarily provided will contact with the compression foot, the amount of the pressure of this contact being somewhat variable but in general in-
5 appreciable and only about sufficient to prevent accidental displacement of the bottle from this position, which may be termed the holding position. Correspondingly, the pressure in this position may be termed the holding pressure. By means of this preliminary manipulation, allowance is made at the outset for variations in the bottle length, it being easily possible to attain approximately the same degree of initial or holding pressure regardless of whether the bottle be
10 long or short. The bottle having been placed in this holding position and thereby exactly gaged, the support or table is locked rigidly in position and the compression foot
15 can then be operated to force the cap down on the bottle to compress the cork disk in the cap to the required extent, which is readily controllable. This cap-seating pressure can be attained by means of a screw or
20 other suitable mechanical movement; and, if desired, by means of an indicating scale or stop means of any appropriate nature the distance through which the manual operating means for applying the cap seating pressure
25 should be moved may be indicated or positively fixed so as to insure attaining the necessarily minimum cap-seating pressure with a given or predetermined movement of the compression foot, thereby
30 avoiding any danger of attaining a crushing pressure.

The cap-seating pressure having been thus applied, so that the cork or other elastic packing of the disk is properly compressed to a predetermined amount, the capping throat or crimping device is then actuated to lock the cap to the bottle by a predetermined amount of movement.

The nature of the invention will be better understood by reference to the accompanying drawings which illustrate a typical embodiment of the invention in a simple form which I have found to be especially advantageous in practice. In these drawings,

Figure 1 is a side elevation of the complete machine or device,

Fig. 2 is a similar view with the principal operating parts shown in central vertical section,

Fig. 3 is an elevation viewed at right angles to Fig. 1; and

Fig. 4 is a top plan of the capping throat.

Referring to the drawings, 10 is a substantially upright standard or bracket adapted to firmly support the various operating parts of the device, said standard being provided with a base 11 adapted to stand squarely on a table or the like, said base being provided with a stud 12 shown

as adapted to project through the table and screw-threaded at its lower end to receive a wing nut 13, whereby the device may be firmly clamped in position on the table. At 14 is a bracket which can be rigidly secured to the standard 10 at various heights thereon according to what general capacity of bottles is to be capped, that is, quarts, pints, or other sizes. Any convenient means of effecting this attachment of the bracket
75 may be adopted. As here shown, said bracket has spaced projections or lugs 15 at the rear coöperating with the vertical guide surface 101 provided at the front edge of standard 10 and grooved on opposite sides
80 as indicated at 16 to receive the ends of adjustable set screws 17, which extend through bosses 18 on the bracket lugs. Additional means may be provided to insure solid mounting of the bracket on the standard at
85 any selected position, such means conveniently taking the form of a clamping screw 19 extending through a depending lug 20 on the bracket 14 and bearing against the vertical standard, any turning movement of the
90 bracket about a horizontal axis being thus resisted and accurate leveling adjustment being facilitated.

The bracket 14 serves as a mounting base for the table or bottle support 21. Said table is so carried on the bracket as to be rapidly shiftable vertically to such different positions as are necessary to compensate for variations in length of bottles of a given capacity as they ordinarily run in commercial lots; and means for effecting this compensating shift and also for conveniently locking the table in any such compensating position are accordingly provided. In the construction illustrated, the table 21 is provided on its under side with skirt or annulus 22, having its lower surface formed as a double cam 23. The cam surfaces 23 bear, respectively, against diametrically opposite cam-abutments 24, carried on the upper side
105 of the bracket 14. The table is secured to an axially disposed post 25 which passes slidably and rotatably through a clamping sleeve 26 formed on said bracket. By this construction, when the table is rotated about its vertical axis, it is elevated or depressed. As here shown, the table is provided with a stop-lug 211 which engages the standard 10 when the full throw of the cam has been reached. The sleeve 26 as here shown is
110 split at 27, suitable clamping means being provided to clamp the sleeve firmly around the post 25, and thus to lock the table 21 at any adjusted position thereof. In the construction illustrated, the clamping bolt 125 28, having an operating handle 29, extends through coöperating lugs 261 of the split sleeve and threads into a nut 281 held stationary in any adjusted position, by a locking pin 282. For turning the table about its
130

vertical axis, a handle 30 may be provided. As shown in the figures, the table is resting on the highest points of the double cam 23.

The overhanging portion or head 31 of the upright standard 10 carries the compression foot 32 and the capping throat device 33 before referred to, together with the necessary operating mechanism therefor. The compression foot is carried at the lower end of a spindle 34, working within a nut or bearing sleeve 35 extending through the head 31, the lower part of said spindle being provided with screw threads 36 working in the internally threaded portion of the sleeve 35. Suitably secured to the upper end of said spindle is an operating handle 37 whereby said spindle may be rotated and thus screwed downward or upward according to the direction of movement of the handle 37. The annular capping-throat device 33 is internally coned to flare downwardly as indicated at 38, and is suitably carried by a holding member 39, vertically slidably on sleeve 35. In the present example, screws 41, threading into tapped bosses 42 on opposite sides of the carrier 39, have washers 411 which marginally engage the under face of the capping throat and enable it to be clamped securely into place in the carrier by turning the screws home. In order to permit ready insertion or removal of the capping throat, it may be provided with peripheral notches 40 of such depth that when the throat is turned so that the notches register with washers the throat will just clear them. Suitable means are provided to force the holder 39 and the throat device 33 downward to effect the skirt-crimping operation, and to return the same upward after the operation is completed. In the present example, a capping cam device comprising a disk 43 revoluble on bushing 35 is provided with a cylindrical skirt or flange 45 to which is secured an operating handle 44, fitting in a socket 441. The lower edge 46 of flange 45 is formed to provide a double cam surface, as shown, bearing against the upper surfaces of lugs or shoulders 47 with which the carrier 39 is provided. In the drawings, the parts are shown in an intermediate position, the handles 37 and 44 having been swung approximately 90° clockwise from starting position.

Coiled spring 48, surrounding spindle 34 and confined between the compression foot and the carrier 39 yieldingly resists downward movement of the capping throat as the capping cam is turned in one direction, and serves to return the same upward to inoperative position when the capping cam device is turned in the opposite direction. The carrier member 39 of the capping throat may be held against rotative movement by means of a forked projection 49 embracing a vertical guide 50 on the upright standard.

The method of employing the bottle capping device of the invention is sufficiently obvious from the foregoing description, but will be summarized for convenience. Assume all the parts to be in starting position, as follows: The compression foot 32 and capping throat 33 are in their uppermost positions; that is, handle 37 is turned approximately 90° counter-clockwise from the position which it occupies in the drawings, or until the lug 371 engages stop 372. Similarly handle 44 is swung approximately 90° counter-clockwise to its stop or starting position. The table support 14 is rigidly secured by means of the set screws 17 at the proper adjusted height on the upright standard 10 for the particular size or height of bottle or jar that is to be capped, and the table support is further secured and properly leveled in position by means of the clamping screw 19. The table clamp handle 29 is in down position, the spindle 25 being therefore free to turn and to move longitudinally in the sleeve 26. The table itself is in its lowermost position which is attained by swinging the handle 30 clockwise substantially 180° from the position shown in Fig. 3. The operator now places the bottle on the table pad and places a crown cap on the bottle top. The table handle is then swung counter-clockwise to turn the table and thereby elevate it until the crown cap enters the capping throat and engages the compression foot 32 with a slight pressure, which is felt by the hand of the operator and the extent of which the operator can thereby judge with sufficient accuracy. As the table is being elevated, the operator may turn the bottle slightly on its base to insure its seating flat on the table pad. With the table held in its elevated position, the operator then pulls the table clamp handle 29 firmly up with his free hand, locking the table in position. The bottle is now exactly gaged between the table and the capping head and is ready to be capped. The operator now grasps the handle 37 and swings it clockwise through a predetermined angle until the lug 371 again engages stop 372. This operation moves the compression foot 32 down through an exactly predetermined distance, thus compressing the cork sealing disk of the crown cap to the necessary extent. The operator next grasps the handle 44 and swings it clockwise until the capping cam has forced the carrier 39 and capping throat 33 down sufficiently far to properly crimp the skirt of the crown over the bead provided on the bottle throat. The throw of the capping cam may be limited to any predetermined distance found to be desirable. For example, a stop screw 52 carried by the capping cam device may be arranged to engage the standard 10 when the capping throat has been forced down a sufficient distance.

tance. The position of this stop screw 52 may be varied, if desired, and to this end one or more additional tapped holes 53 may be provided on the cylindrical portion 45 of the capping cam device to enable setting the stop screw at different angular positions thereon. This arrangement is convenient because it enables adjustment for greater downward movement of the capping throat 10 when the latter becomes badly worn after long use.

The operations above described complete the capping of the bottle or jar. To release the capped bottle or jar, handles 37 and 44 15 are successively swung counterclockwise into their starting positions. The operator then grasps the bottle near its base with one hand, and at the same time loosens the table clamp by pushing down on handle 29. The 20 table thus released will return to its lowest position by gravity, and the capped bottle or jar may then be removed from the table.

As the bearing surfaces on the capping cam and throat carrier wear, the distance 25 relation between the compression foot and the throat may after long use change sufficiently to require adjustment of the parts. In order to restore the original distance relation, the set screw 373 in the handle casting 374 is first loosened. The handle casting is then turned counter-clockwise from the position shown in the drawings until the lug 371 is against the stop 372, and the casting is raised about one-eighth of an inch 30 above the upper surface of the head 31 of the frame casting, in which position it may be held temporarily in any suitable manner as by means of thin pieces of wood or cardboard inserted between the casting and the 35 head. The compression screw spindle 34 is then turned slightly in the proper direction to raise the compression foot a trifle. This may be conveniently accomplished by means of a screw driver engaging screw 321 40 which holds the compression foot to the compression screw. An unused crown cap is next pushed into the sealing throat, and if it does not seat on the crimping surface of the throat, the compression screw should be 45 turned back still farther in the same direction as before. When proper seating of the cap in the capping throat is finally accomplished, the handle casting is clamped to the screw spindle 34 by tightening set screw 50 55 373, and the cardboard or other temporary spacing means is removed. With the crown cap held properly seated against the capping throat edge, the handle casting 374 is turned clockwise until the compression foot just touches the top of the crown. Keeping 60 the handle casting in this position, the crown cap is then removed, the compression screw is held against movement by means of a screw driver, and set screw 373 is again 65 loosened, and the handle casting turned back

counter-clockwise into starting position. The handel casting is then raised about one-eighth of an inch, and the set screw 373 tightened to clamp the same securely to the compression screw. The capping tool is 70 now adjusted to compress the cork of a crown the same amount as when the tool was new, and this is the only adjustment required.

While the invention has been described 75 more particularly in connection with bottle capping devices designed especially for domestic use, certain novel features of the construction disclosed are applicable to machines adapted for operation on a larger 80 scale, and the scope of the invention is to be understood as correspondingly broad.

Since, by the construction shown, the bottles, notwithstanding deviations from standard size always have their tops brought 85 to a predetermined position relative to the capping mechanism, the latter, comprising the compression foot and the capping-throat device, may have always the same amount of downward movement, thus insuring the 90 same amount of compression of the cork and the same amount of crimping of the skirt of the crown. This is not the case where springs are relied on, since these change 95 with use.

Since a large part of the construction herein disclosed is in the form of simple castings requiring substantially no machine work in finishing and assembling, such work being limited to a few parts, the machine is 100 economical in construction, yet durable and reliable. The absence of springs for determining the capping pressure is an especially desirable characteristic.

What I claim is:

1. In bottle capping apparatus, the combination, with a standard and means for securing the same to a support, of a reciprocable compression foot, a reciprocable capping-throat device, both supported by 110 said standard, separate manually operable means for actuating said compression foot and capping-throat device independently, a bottle support carried by said standard in fixed alinement with said compression foot, and manually operable means for moving said bottle support toward and away from said compression foot and for rigidly holding 115 said bottle support against movement.

2. In bottle capping apparatus, the combination, with a mounting pedestal having an overhanging upper portion, and means for securing said pedestal to a suitable support, of an internally threaded bushing supported by said overhanging portion of the 120 pedestal, a compression foot having a spindle threaded to work in said bushing, a handle for turning said spindle, a capping-throat device vertically slidale on said bushing, a cam device rotatable on said bush- 125 130

ing to force said capping-throat device downwardly, a handle for rotating said cam device, a bracket adapted for rigid attachment to said pedestal at different heights 5 thereon, a bottle supporting table mounted on said bracket in fixed alinement with said compression foot but movable on said bracket toward and from said foot, manually operated cam means for effecting such 10 movement of the table, and means for locking the table in any adjusted position on said bracket.

3. In bottle capping apparatus, the combination, with a compression foot, a capping-throat device, and means angularly movable to impart positive predetermined thrust movement to said compression foot and capping-throat device separately, of a bottle support independently movable toward and away from said compression foot and capping-throat device, and means for holding said bottle support in adjusted position.

4. Bottle capping apparatus as set forth 25 in claim 1, including stop means to limit the operative movements of said compression foot and capping-throat device.

5. Bottle capping apparatus comprising, in combination, a bottle support and a capping 30 head relatively movable bodily toward and away from each other to preliminarily gage between them a bottle surmounted by a cap, and means whereby relative separating

movement of said support and capping head after such preliminary adjustment is rigidly 35 opposed, said capping head comprising a compression foot arranged to engage the cap on said bottle in such preliminary gaging position, means for imparting to said compression foot a cap-compressing stroke 40 of predetermined length, and a capping-throat device operable independently of said compression foot to force the cap skirt into locking engagement with the bottle while the cap is so held under compression. 45

6. Bottle capping apparatus comprising, in combination, a rectilinearly movable compression foot, a bottle support adjustable toward and away therefrom, means operable to hold said support rigidly in adjusted position, a capping-throat device encircling said compression foot and movable parallel therewith but independently thereof, means operable to impart a positive non-yielding cap-compressing stroke to said compression 55 foot, and separate means for actuating said capping-throat device.

7. Bottle capping apparatus as set forth in claim 6 further characterized by the provision of spring means acting upon said capping throat device and tending to move it 60 out of operative position.

In testimony whereof I hereunto affix my signature.

ARNOLD CRAWFORD MASSIE.
